FIG. 1 is a left perspective view of an actuator for an aerosol spray bottle, and an aerosol spray bottle, showing the new ornamental design;

FIG. 2 is a right perspective view of the actuator for an aerosol spray bottle, and an aerosol spray bottle, showing the new ornamental design;

FIG. 3 is a left view of the actuator for an aerosol spray bottle; FIG. 4 is a right view of the actuator for an aerosol spray bottle;

FIG. 5 is a back view of the actuator for an aerosol spray bottle, wherein the front view is a mirror image thereof;

FIG. 6 is a top view of the actuator for an aerosol spray bottle; FIG. 7 is a bottom view of the actuator for an aerosol spray bottle; and,

FIG. 8 is a perspective view of an aerosol spray bottle.

The broken lines shown in the drawings are included for the purpose of illustrating structural environment and form no part of the claimed design.
